UNITED STATES PATENT OFFICE.

JAMES T. POWERS, OF CHICAGO HEIGHTS, ILLINOIS.

DISPLAY APPLIANCE.

Application filed May 4, 1928. Serial No. 275,059.

My invention relates to display or advertising appliances, especially, but not necessarily restrictedly, to upright structures adapted to rest on the ground or sidewalk and to support a legend-bearing plate in prominent exhibition position, whereby the attention of passers-by is directed to the advertising matter.

The leading aim or prime object of the invention is to provide a structure of this character which is simple in construction, which is strong and rugged and hence able to withstand relatively severe usage, which can be economically manufactured, and which is comparatively pleasing in appearance.

A further purpose of the invention is the production of an apparatus of this type and style which is capable of accommodating display plates or members of different sizes.

To enable those skilled in this art to fully understand the invention, both from structural and functional standpoints, in the accompanying drawing, forming a part of this specification, I have illustrated a present, desirable and preferred embodiment of the invention and throughout the views thereof, for simplicity, like reference characters have been employed to designate the same parts.

In this drawing:

Figure 1 is an elevation of the appliance showing the base in central vertical section;

Figure 2 is an enlarged vertical central section on line 2—2 of Figure 1;

Figure 3 is a horizontal section on line 3—3 of Figure 1; and

Figure 4 is a fragmentary detail section of the display-plate supporting ring or band.

Referring to the several views of the drawing, it will be observed that the base of the display apparatus includes a metal ring 11 adapted to rest on the ground, sidewalk, floor or the like, the opposite sides of such circular element having riveted to them at 12, 12, the downturned ends 13, 13 of a metal bar 14 extended across the center of the ring at which middle point such bar carries a threaded socket-piece 15 riveted thereto at 16, 16.

The member 15 is also connected to the ring by a pair of diametrically oppositely-disposed bars 17, 17 fastened thereto by rivets at 18, 18 and also having downwardly-bent ends 19 riveted at 20 to the base-ring 11.

Thus, these several strongly-united elements constitute or form a supporting-base of suitable shape and of adequate strength.

The central threaded socket or cavity of

the part 15 demountably receives the correspondingly screw-threaded, lower end of an upright, tubular standard 21, the upper threaded end of which is similarly accommodated in an internally threaded socket portion 22 on the under side of a curved supporting-member 23 having a longitudinal channel 24 in its upper surface designed to hold or admit the peripheral, outstanding, hollow rib 25 of a circular, metal, frame element 26 riveted at 27, 27 on the top of the supporting-member 23.

As is illustrated, the hollow interior or internal-channel of the rib 25 receives the circular margin of a round, sheet-metal display-plate 28 on one or both faces of which the advertising or other matter to be exhibited is provided.

In order that the appliance may be used with plates of somewhat different diameters, the ring or frame member 26 is not made continuous but its ends 29, 31 are joined together by a connecting piece 32 which allows or permits adjustment or variation of the space or distance between such ring ends.

Such joining or uniting element is shaped in cross-section to conform to the outer surface of the ring and its one end is riveted at 33 to one end of the ring, but the other end portion of the connector is provided with a series of pairs of holes 34, 34 any pair of which may receive bolts 35, 35 extended through holes in the adjacent or other end 31 of the ring.

Thus, by inserting the bolts in the different pairs of connector holes, the size of the ring may be somewhat modified as circumstances may require.

Since the display or exhibition plate is round, it might have a tendency to turn in its supporting ring and thus cause the advertising matter to occupy a sloping or tilted relation.

To preclude the occurrence of such a contingency, suitable means are provided to lock the plate against such turning action.

To this end, a suitably-bent, sheet-metal clip 36 is fastened by a screw 37 to a face of the support 23 and by a bolt 38 against the adjacent surface of the plate 28.

From the foregoing, it should be manifest that the appliance can be shipped in knocked-down condition and the parts may be readily assembled when required, the display plate is held firmly in position by an expandable and contractible encircling frame, and the plate is

prevented from shifting or moving out of proper or correct exhibition position.

Those acquainted with this art will readily understand that the invention, as defined by the appended claims, is not limited to the exact and precise details of structure presented and that these may be modified within comparatively wide limits without departure from the heart and essence of the invention and without the sacrifice of any of its substantial or material benefits or advantages.

I claim:

1. In a display-appliance, the combination of a base, a standard supported by said base, a ring having an internal circumferential channel mounted on the top of said standard, means adjustably securing together the ends

of said ring, a display-plate mounted in said ring with its edge accommodated in said channel, and means to prevent said plate from turning in said ring.

2. In a display-appliance, the combination of a base, a standard supported by said base, a grooved support on the top of said standard, a ring having an external hollow rib affording an internal circumferential channel mounted on said support with its rib in said groove, and a display-plate mounted in said ring with its edge portion accommodated in said channel.

In witness whereof I have hereunto set my hand.

JAMES T. POWERS.
